UNITED STATES PATENT OFFICE.

DUNY A. SCHUTT, OF PERU, INDIANA, ASSIGNOR TO THE PERU ELECTRIC MANUFACTURING COMPANY, OF SAME PLACE.

MULTIPLE-CIRCUIT BLOCK.

SPECIFICATION forming part of Letters Patent No. 595,078, dated December 7, 1897.

Application filed April 16, 1897. Serial No. 632,440. (No model.)

To all whom it may concern:

Be it known that I, DUNY A. SCHUTT, a citizen of the United States, residing at Peru, in the county of Miami and State of Indiana, have invented or discovered a new and useful Improvement in Multiple-Circuit Blocks, of which the following is a full, clear, and exact description, reference being had to the accompanying drawings, forming part of this application, in which—

Figure 1 is a face view of my improved three-wire multiple-circuit block. Fig. 2 is a vertical longitudinal section taken on the line II II of Fig. 1. Fig. 3 is a top edge view. Fig. 4 is a cross-sectional view on the line IV IV of Fig. 1. Fig. 5 is a similar section on the line V V.

My invention consists of a circuit-block for use in making branch connections at either side from a three-wire system; and it comprises a block built up of sections of porcelain or other insulating material with suitable metallic connections to provide for distribution of the current, as I shall hereinafter set forth.

In a previous application, patented March 10, 1896, Serial No. 556,028, I have shown and described a multiple-circuit block for use in a two-wire system.

The object of the present invention is to provide means for making connections from either side of the block or from both sides without crossing wires in a convenient and workmanlike manner and to construct and join the sections in a substantial and practical way.

Referring to the drawings, 2 3 are sections of porcelain or other insulating material joined together by three metallic connecting-bars 4 5 6, secured to the blocks by screws 7, passing through the strips and porcelain and screwed into the bushings 8. Terminal connections 9 are inserted in suitable recesses in the block, to which are introduced in the outside connections the positive wires 10, a negative wire 11 being inserted in the middle connection, the wires being fastened by screws 12. From the outside positive connections 9 fuses 13 lead to a holding-screw 14, making electrical connection through the bushings 8 and screw 7 with the connecting-bars 4 and 6, re-

spectively, thus charging such bars with a positive current. A similar connecting-fuse 15 transmits a negative current through holding-screw 16 and a similar connecting-screw 55 to the bar 5 at the back, thus charging such bar with a negative current.

From the back bars 4 and 6 the positive current is introduced to the front of the block by means of screws 7' passing through the 60 bar and porcelain and into a bushing provided with binding-screw 17. In a similar manner the negative current is introduced to the front of the block by means of screws 7'', tapped into front cross-bars 18, having at 65 each end binding-screws 19.

Ranged along each outer edge of the block are double binding-screw connections 20, from which pairs of wires lead off to any desired point, and to the connections 20 lead 70 the fuses 21 22 from the binding-screws 17 and 19, respectively, thus supplying positive and negative currents to the pairs of wires so arranged. The same arrangement is observed on each side, and while I have shown 75 but two sections of insulating-blocks a considerable number may be so joined by extending the connecting-bars at the back and increasing the number of side connections.

I have shown the block as provided with a 80 series of separating-ribs 23, which serve to strengthen the construction and to protect the exposed parts from injury or short-circuiting.

What I claim is—

1. A circuit-block for use in making branch electrical connections consisting of two or more sections of insulating material secured together by metallic bars at the back, main-wire sockets with fusible electrical connections to the bars, and branch connections through the block and to binding-screws at the side, substantially as set forth.

2. A three-wire-circuit block consisting of two or more sections of insulating material 95 secured together by a central metallic bar at the back and a similar bar at each side, countersunk, main-wire bushings secured on one of the sections with fusible electrical connections to the bars, electrical connection through 100 the block from the side bars to binding-screws at the sides of the block, and electrical con-

nections through the block from the center bar to cross-bars provided with means for making electrical connection to the binding-screws, substantially as set forth.

- 5 3. A three-wire-circuit block consisting of two or more sections of insulating material secured together by a central metallic bar at the back and a similar bar at each side, countersunk, main-wire sockets secured to one of
10 the sections with fusible electrical connections to the bars, electrical connection through the block from the side bars to binding-screws

at the sides of the block, and electrical connections through the block from the center bar to cross-bars provided with means for 15 making electrical connection to the binding-screws, with separating extended ridges on the face of the block, substantially as set forth.

In testimony whereof I have hereunto set my hand this 27th day of January, 1897.

DUNY A. SCHIUTT.
